PATENTED JULY 3, 1906.

J. MALMGREN.
NAILING IMPLEMENT.
APPLICATION FILED JULY 7, 1905.

UNITED STATES PATENT OFFICE.

JOHN MALMGREN, OF CERESCO, NEBRASKA, ASSIGNOR OF ONE-HALF TO HERMAN WYQUIST AND ONE-HALF TO HUGH LEAL, BOTH OF CERESCO, NEBRASKA.

NAILING IMPLEMENT.

No. 825,141.

Specification of Letters Patent.

Patented July 3, 1906.

Application filed July 7, 1905. Serial No. 268,696.

To all whom it may concern:

Be it known that I, JOHN MALMGREN, a citizen of the United States, residing at Ceresco, in the county of Saunders and State of Nebraska, have invented a new and useful 5 Nailing Implement, of which the following is a specification.

This invention relates to nailing implements, and while especially designed for use 10 in shingling may be used with equally satisfactory results for other purposes.

The object of the invention is to provide a nailing implement embodying new and improved features of reliability and convenience.

15 A further object of the invention is to provide a nailing implement having a nail-box formed to assort and arrange nails upon the conveyer with a great degree of accuracy.

With these and other objects in view the 20 present invention consists in the combination and arrangement of parts, as will be hereinafter fully described, shown in the accompanying drawings, and particularly pointed out in the appended claims, it being understood 25 that changes in the form, proportions, size, and minor details may be made without departing from the spirit or sacrificing any of its advantages.

In the drawings, Figure 1 is a view of the 30 improved nailing implement in side elevation. Fig. 2 is a top plan view of the improved nailing implement. Fig. 3 is a bottom plan view of the nailing implement. Fig. 4 is a detail view of the driving-head and nail-feed from the under side and with a nail in position to be set. Fig. 5 is a transverse sectional view 35 of the nail-box on line 5 5 of Fig. 1. Fig. 6 is a transverse sectional view of the nail-conveyer, taken on line 6 6 of Fig. 1.

40 Like characters of reference designate corresponding parts throughout the several views.

In its preferred embodiment the nailing implement forming the subject-matter of this application comprises a driving-head 1, having a serrated driving-face 2 and a splitting-knife 3 secured thereto, as by the bolt 4. Upon opposite sides of the driving-head 1 are secured the bars 5 and 6 by the bolt 4 and forming between them the nail-conveyer slot 50 7 and the nail-holding opening 8. The ends

of the bars 5 and 6 opposite the head 1 are spaced, as by the washer 9, and clamped thereon by the bolt 10.

Intermediate the ends of the bar 5 a handle 11 is rigidly secured, as by the bolts 12, 55 passing through the bracket 13. Adjacent the head 1 the bars 5 and 6 are provided with a transverse slot 14, curved to conform to the curved lower ends 15 of the bars, and therein is mounted the feed-plate 16, curved to conform to the slot and carried upon the end of the lever 17, pivoted at 18 to the bracket 13. Upon the end of lever 17 opposite the feed-plate is provided thumb-piece 19 adjacent the handle 11, and between the bracket and 60 the thumb-piece is disposed the spring 20, arranged to hold the thumb-piece normally away from the handle and the feed-plate in position shown in Figs. 2 and 3.

The feed-plate is provided with an arcuate 70 slot 21 and with an open-ended slot 22, communicating with the slot 21 and disposed obliquely to a radius from the pivot 18 to the slot 21. The feed-plate 16 is also provided with a nail-separating point 23 and a curved 75 arm 24.

The nail-box is formed, as shown at Fig. 5, with the side 25 approximately level with the side 26 relative to the nail-conveyer, which is disposed nearer the side 26 than to the side 80 25 and forms a slot opening through the bottom of the nail-box, as shown at 27. Along the side of slot 27 adjacent side 25 a deflector-plate 28 is secured, forming throughout its length with the side 26 a substantially concave channel with the slot 27 at its bottom, as shown in detail in Fig. 5. The deflector-plate 28 extends throughout only a portion 85 of the length of the nail-box, as shown in Fig. 2, and the side 25 of the nail-box is disposed 90 relative to the conveyer and below the deflector-plate 28 as it approaches the lower end, so that, as shown at 29 in Fig. 5, the side 25 is curved considerably below the plate 28. Above the conveyer and intermediate the 95 ends of the nail-box a baffle-plate 30 is secured to the side 26 and arranged to spread out the nails 31 in their passage. The nail-box is provided with any approved form of closure, as the sliding cover 32, having the 100

lips 33 engaging the longitudinal flanges 34 of the box. To prevent the nails 31 from being thrown from the conveyer, a cover 35 is secured above the slot of the conveyer, as by 5 the angular portion 36, secured to the bar 6, leaving a slot 37 between the cover and the bars for the insertion of a tool to move the nails in case the passage becomes clogged for any reason.

10 With the cover 32 removed, as shown in Fig. 2, nails may be placed in the nail-box to partially fill the box. By holding the box in an upright position and oscillating it in a plane longitudinal with the box the nails will 15 be thrown from one end of the box to the other. The motion described is the motion naturally employed in driving a nail with the driving-face 2. When the nails are traveling from the upper to the lower end of the 20 box, by reason of the oscillation they seek to travel in the concave formed by the side 26 and the plate 28. The concavity of the side and plate will tend to turn the nails longitudinal with the box, and when so turned the 25 pointed end of the nail will fall through the slot 27 and the head be retained by the strips 5 and 6, when they will slide by gravity downwardly through the conveyer-slot 7 and held therein by the cover 35. After the 30 nails have passed beyond the forward end of the deflector-plate 28 they fall into the side 25, where it is curved below the deflector-plate, thus clearing from the conveyer the 35 nails which might interfere with the free passage of the nails hanging through the conveyer-slot. Upon the return movement of the implement the nails are returned to the rear end, from which point they slide easily upon and over the plate 28. When the 40 rank of nails reach the lower end of the feed, they are stopped by the feed-plate until the lever 17 is manipulated, when the point 23 passes between the first and second nail of the rank, forcing the first nail to follow the slot 22, and the remaining nails are held by the edge 24. 45 As the feed-plate moves transversely the nail is forced downward in the slot 22 until it is engaged and held within the slot 21 and between the feed-plate and the side bar 5, as shown in Figs. 1 and 4. The nail is then 50 partially driven by striking the implement and the clamped nail. When the nail is set, the release of the spoon 19 will release the head of the nail, when the driving may be completed by striking the head of the nail 55 with the driving-face 2. The motion of driving will throw the nails from one end to

the other of the box and keep the conveyer filled.

Having thus described the invention, what is claimed is—

1. A nailing implement having a driving-head, a nail-guide terminating short of the driving-head, and a slotted nail selecting and clamping means arranged to separate the successively lowermost nails, and portions of the side walls of the slotted selecting means and the nail-guide serving to clamp and hold the separate nails during the movement of the implement in a setting or partial driving of the nail, and for releasing the nail to permit the subsequent action of the driving-head thereon. 65

2. A nailing implement having a nailing-head and provided with a grooved guide 75 along which nails may travel in the direction of the head, a selecting and clamping device crossing the plane of the groove, and slotted to permit the passage of the successively lowermost nails, a portion of the wall of the 80 slot coacting with one of the walls of the groove to clamp and hold the separate nails during the preliminary setting or partial driving operation, the slot being widened to permit the release of the nail for the subsequent action of the head thereon. 85

3. A hand-nailing implement, including a nailing-head and nail-box, a rigid nail-conveyer extending from the box to the head and provided with a widened discharge end, 90 a main handle secured to the conveyer, a nail-feed comprising a pivoted lever carrying a plate provided with an arcuate slot and with a communicating slot oblique to a radial line extending from the pivot, a portion of the 95 wall of the slot serving in connection with a portion of the nail-conveyer to hold the nails in position for initial driving or setting, and an operating-handle carried by said lever.

4. In a nailing implement, a nailing-head, 100 a nail-box having a nail-receiving slot, a conveyer with which said slot communicates, an arcuate plate arranged at one edge of the slot and serving to guide the nails thereinto, and a guard-plate extending across the plane of 105 the slot and partly over said arcuate plate to assist in directing the nails into said slot.

In testimony that I claim the foregoing as my own I have hereto affixed my signature in the presence of two witnesses.

JOHN MALMGREN.
